H. W. LUSCHER

METHOD OF DRYING GELATIN.

Filed March 30, 1922

HARRY W. LUSCHER
BY

Louis Leedles

ATTORNEY.

UNITED STATES PATENT OFFICE.

HARRY W. LUSCHER, OF CARROLLVILLE, WISCONSIN, ASSIGNOR TO UNITED STATES GLUE COMPANY, A CORPORATION OF WISCONSIN.

METHOD OF DRYING GELATIN.

Application filed March 30, 1922. Serial No. 548,074.

To all whom it may concern:

Be it known that I, HARRY W. LUSCHER, a citizen of the United States, residing at Carrollville, town of Oak Creek, State of Wisconsin, have invented a certain new and useful Method of Drying Gelatin, of which the following is a specification.

In the manufacture of gelatin, particularly of that desired for edible and photographic purposes, it is important that viscosity tests be as high as possible and that the product be as nearly sterile as possible. Gelatin forms a natural culture medium for the growth of bacteria and it must be free from antiseptics or disinfectants of any kind, particularly if it is desired for use as a food.

In manufacturing gelatin the raw material from the liming is first extracted at temperatures varying from 155 to 165 degrees Fahrenheit for a period of five to six hours. It is then evaporated under a vacuum of approximately 25 inches which causes it to boil in the neighborhood of 138 to 140 degrees Fahrenheit, and these temperatures being above Pasteurizing temperatures result in what is then a practically sterile product. If the completion of the gelatin is thereafter carefully done, preferably in apparatus and pipes lined with glass so that it can not take up any metal which it is very prone to do, it can be kept pure and sterile up to the time of drying.

It is customary to partially harden the gelatin by means of spreading machines of the general type disclosed in Letters Patent No. 1,309,995, issued to C. Bates under date of July 15, 1919, and then spread the partially hardened gelatin on nets which are transferred to drying alleys. There is practically no danger of contamination by bacteria in the spreading machine owing to the low temperatures used, but when the gelatin nets are spread in the drying alleys and subjected to a flow of heated air with temperatures varying from 85 to 120 degrees Fahrenheit, the danger of contamination is markedly increased.

Experience has determined that as the gelatin is drying on the nets in the drying alley bacteria enter with the air and lodge on the surface of the gelatin. The numbers and kinds of bacteria present, of course, vary through quite wide ranges depending upon the temperatures and relative humid-

ity, cold, dry air being comparatively bacteria free, while moist, warm air is generally highly contaminated. There may be, and often is, comparatively little propagation of the bacteria at this time because of the rapid dessication of the gelatin. This, however, does not kill the bacteria but merely causes them to lie dormant and they become active again when the gelatin is mixed with water and commence to propagate, with a resultant deleterious effect upon the gelatin solution. This is particularly noticeable with organisms of the liquefying type. It is also true with many other kinds of organisms present.

Experiments have indicated the inadvisability of, and various pure food departments have precluded the use of, disinfectants which are dissolved in the gelatin itself such as are customarily used in the manufacture of glue, e. g., zinc sulphate, etc. Experiments have also shown that most gaseous disinfectants must be used very sparingly, if at all, as they are readily absorbed by the gelatin rendering it insoluble and if present in any quantities are really adulterants. For example, it is possible through very careful manipulation to use chlorine gas or formaldehyde gas, but unless the quantities used are carefully regulated and very minute, in the case of chlorine, for example, in the proportion of one part chlorine to 100,000 parts of air, the excess chlorine is absorbed by the gelatin causing it to become insoluble in water and the resultant product is therefore worthless. The same thing is true with formaldehyde gas and other so-called gaseous disinfectants.

I have discovered that substantially sterile gelatin may be made by conducting the drying in the drying alleys in the presence of ozone. The nascent oxygen produced by the ozonized air oxidizes the bacteria-laden dust producing an antiseptic air, and the ozone is not absorbed by the gelatin and it does not affect the qualities of the gelatin whatsoever. So far as the gelatin itself is concerned the ozonized air is inert but it exerts a powerful selective action on the dust particles, bacteria, etc., and therefore may be used in quantities without injury to the gelatin.

I find that as a matter of economy it is advisable to first remove the excess of dust by passing the air through mechanical fil-

ters, such as canton flannel bags, as this reduces the amount of work that must be done by the ozone; the use of filters alone, however, has not proven practicable.

5 I append drawings as a part of this specification showing one method of introducing ozone in actual practice.

In the drawings,

10 Figure 1 represents the plan view of the alley with coils, fan and ozone machine; and

Figure 2 is a side view of the alley, parts being broken away to show the interior thereof.

15 In the drawings 1 represents the alley and 1' the neck thereof, 2 the spreading nets in position which are held on the racks 3; 4 is the fan driven by the motor 5 through gearing 6 or other suitable means, 7 are the 20 heating coils for heating the air which is drawn through the filters 8, which are made with a lip or ring 9 which fits over the perforated plate 10 and are held at the bottom by a cord 11 fitting into an eyelet 12.

25 Part of the air, approximately 10 per cent, but the exact amount of which may vary, is taken from the chamber 13 in which the filters 8 are located, through a by-pass 14, into the ozonizing machine 15 and is then 30 delivered through a by-pass 16 into the neck of the alley 1' on the suction side of the fan, where it is commingled with the other air by the turbulence created by the fan and forced in the direction of the arrows through the 35 alley 1 and across the surface of the nets 2 and out at the discharge end of the alley.

The ozonizing machine 15, together with the by-passes 14 and 16 are preferably located near the top of the neck of the alley 1' and are shown in the drawings as suspended on a platform 17 by hangers 18. This is not necessary but has the advantage of getting the machine out of the way so that the operator has room enough to walk 45 underneath the platform 17 without striking his head in case it is desired to walk alongside of the alley.

When in operation the air is drawn in through the filters 8 into the chamber 10 by 50 the suction of the fan 4. A portion thereof

goes through the by-pass 14 through the ozonizing machine 15 and returns to the neck of the alley 1' through the by-pass 16. The major portion of the flow is drawn through the heating coils 7 and the flows 55 converge in front of the fan 4 and are then forced through the alley 1 and over the nets 2 and out of the discharge end. The turbulence of the fan is such that the ozonized air is completely mixed with the unozone 60 air and the rate of flow is such that sufficient contact is made and time allowed between the time the ozonized air comes in through the by-pass 16 and the time the air strikes the first net 2 so that the air is completely sterilized.

As an indication of the remarkable effects that I have produced by the use of ozonized air, I have been enabled to reduce the bacteria content of liquefying organisms in gelatin from 8,000,000 per gram to 1,000 per gram and a reduction of a total bacteria count from 26,000,000 per gram to 380,000 per gram.

The apparatus indicated in the drawings 75 is, of course, subject to obvious changes and variations in the method of applying the ozone.

Having fully described my invention what I desire to cover as new and claim is:

1. The method of drying substantially 80 sterile gelatin and preventing its contamination during drying, which consists in placing the gelatin in a drying compartment and subjecting it to the drying action of ozonized air while in said compartment.

2. The method of drying substantially 85 sterile gelatin and preventing its contamination during drying, which consists in placing the gelatin in a drying compartment, 90 filtering the drying air to remove excess foreign matter, heating a part of this drying air and passing another part of the drying air through an ozonizer, mixing the heated air with the ozonized air and subjecting the gelatin to the drying action of 95 this mixture of heated ozonized air while in said compartment.

HARRY W. LUSCHER.
